HOLDER FOR METAL WOOL

Abe Schimel, New York, N. Y.

Application November 27, 1943, Serial No. 511,956

3 Claims. (Cl. 15—209)

This invention relates to an improved holder for metal wool and the like. The principal object thereof is to provide a simple device which will securely hold a preshaped pad of metal wool, thus providing a safe and effective means for cleaning household utensils.

Metal wool (sold in the form of pads) is a common household cleaning medium, especially useful for cleaning aluminum utensils and the like. The use of such metal wool frequently results in particles or shavings of the wool becoming imbedded in the hand or fingers of the user, resulting in infection often. Despite its excellent cleaning properties, the use of metal wool always presents this drawback and danger. The principal object of this invention therefore is to provide a novel metal wool holding device which can be firmly gripped and held by the user and in which there is no opportunity for the fingers or the hand to contact the metal wool.

Another object of the invention is to provide a metal wool holding device having simple and effective means for holding and releasing the metal wool pad.

Another object of the invention is to provide a metal wool holding device which is simple to assemble and use and which is most effective in operation.

Other objects of the invention will be stated in the annexed description and drawing, which set forth one embodiment.

Fig. 1 is a transverse sectional view of the improved device, showing the pre-shaped metal wool pad held thereby.

Fig. 2 is a sectional view on line 2—2 of Fig. 1.

Fig. 3 is a perspective view of the pre-shaped metal wool pad.

Fig. 4 is an elevational view of the holding device illustrating the manner in which the metal wool pad (shown in broken lines) is released from the device.

Fig. 5 is a sectional view on line 5—5 of Fig. 3.

Referring to the drawing, the holder device includes a handle member H having a circular cross-section and which is preferably made of wood or any other suitable rigid material. Said handle member H has a reduced or constricted portion 10 dividing the same into the knob or upper part 11 and the lower part 12. I have designated said upper part 11 as a knob for the reason that this is the gripping portion of handle member H.

As shown in Figs. 1 and 4, the circumferential wall of lower part 12 of handle member H tapers outwardly from reduced portion 10 to the base 55

thereof. The diameter of the base of lower part 12 is greater than the diameter of knob 11. The significance of this will be hereinafter explained.

As shown in Fig. 1, a circular recess 13 is formed in the top wall of knob 11. A cup-shaped metal liner 14, having the outwardly extending peripheral flange 15 is located within said recess 13, said liner frictionally engaging the walls of said recess. It will be noted that flange 15 is substantially flush with the top wall of knob 11.

Handle member H is provided with a central longitudinal bore 16 which is aligned with an opening 17 in the bottom wall of liner 14. Said bore 16 is adapted to accommodate a pin 18 having the enlarged head 19, said pin being slidable within said bore 16. The opposite end 20 of pin 18 is threaded to receive the metal plate 21. The peripheral edge of said plate 21 is formed with a plurality of upwardly curved serrations or teeth 22. Said plate 21 is provided with the depending integral boss 23 to afford a greater threading area for connecting said plate to pin 18.

As shown in Fig. 1, a conical shaped spring 24 is mounted on pin 18 between the bottom face of head 19 and the bottom wall of liner 14, said spring being substantially housed in said recess 13. It will be noted that the diameter of head 19 is slightly smaller than the diameter of liner 14 and recess 13, so that said head 19 may enter 30 said recess when spring 24 is compressed.

Figs. 3 and 5 show the pre-shaped pad of metal wool P which is held by plate member 21. Said pad P is preformed with the inwardly extending clamping collar 25 and the annular recess 26. Said pad P may be formed of any suitable type of metal wool ordinarily used for cleaning utensils and the like.

Pad P is assembled with the holding device by depressing head 19 of pin 18 until said head is 40 substantially flush with the top wall of knob 11. Spring 24 is thereby compressed within recess 13 and plate member 21 is moved downwardly away from the bottom wall of lower part 12 of handle H. Pad P is then placed upon plate 21 so that teeth 22 enter the recess 26 of said pad.

Upon the release of pressure on head 19, spring 24 will become extended thus forcing head 19 upwardly to the position shown in Fig. 1. Plate 21 will also be forced upwardly thus clamping collar 25 between teeth 22 and the bottom wall of the lower part 12 of handle H. In this position (see Fig. 1) the top face of collar 25 will abut the bottom wall of portion 12 of handle member H. The top planar face of plate 21 will also abut the bottom planar wall of portion 12.

In this manner, pad P is securely clamped and held by the holding device, thus presenting a useful household article for cleaning aluminum utensils and the like. The upwardly curved teeth 22 of plate member 21 assist in the positive holding of pad P. In the operative position shown in Fig. 1, spring 24 serves to maintain plate member 21 in abutting relation with the bottom wall of lower portion 12 of the holder.

Pad P can be removed simply by pressing head 19 downwardly until plate 21 no longer abuts or contacts the bottom wall of portion 12 and then removing the pad from plate 21. Fig. 4 clearly shows this.

It will be noted that the diameter of pad P is slightly smaller than the diameter of the base of lower portion 12 of handle member H. The purpose of this is to avoid any contact of the fingers or hand of the user with pad P.

In using the device, the hand of the user is placed upon knob 11 so that the device may be effectively gripped and held. The fingers of the user are naturally placed in the circumferential groove formed by reduced position 18 of handle member H. In this manner, there is no opportunity for the fingers or hand to come in contact with the metal wool. Likewise, by making the diameter of the base of lower portion 12 larger than the diameter of knob 11, further means are provided for preventing the metal wool from contacting the fingers or hand of the user.

I have shown and described a preferred embodiment of my invention but it is obvious that numerous changes and omissions may be made without departing from its spirit. For example, metal liner 14 may be dispensed with entirely. The proportions and size of handle member H may be varied as desired.

Of course, I do not wish this invention to be limited to the use of metal wool pads. Any type of cleaning pads may be used in conjunction with the improved device.

What I claim is:

1. A holding device for metal wool comprising a handle member having a reduced portion dividing the same into an upper gripping portion and a base portion, the diameter of said base por-

tion being greater than the diameter of said gripping portion, said gripping portion having a recess formed in the top wall thereof, said handle member having a central longitudinal bore formed therein, said bore communicating with said recess, a pin having an enlarged head slidably positioned in said bore and passing through said recess, the diameter of said head being smaller than the diameter of said recess, a pad-holding plate member secured to the opposite end of said pin below the bottom wall of the base portion of the handle member, the peripheral edge of said plate member being formed with a plurality of upwardly curved serrations, 5 a spring mounted on the shank of said pin intermediate the head of said pin and the bottom wall of the recess, said spring being substantially housed in said recess, said spring urging the top face of the plate member to abut the bottom wall of the base portion of the handle member.

2. A holding device for metal wool comprising a handle member having a bottom planar wall, a recess formed in said handle member, a longitudinal bore centrally located in said handle and communicating with said recess, a pin having an enlarged head slidably positioned in said bore and passing through said recess, a pad holding plate threadedly secured to the opposite end of said pin, said plate having an upper central planar portion in abutting relationship with said bottom planar wall of said handle member and a peripheral portion spaced from the bottom planar wall of said handle member, a pad having its peripheral edges positioned between the bottom planar wall of the handle and the peripheral portion of said plate, and spring means mounted on said pin between the head of the pin and the base of the recess, said spring urging the 10 central upper portion of the plate member and the peripheral portion of the plate member and peripheral edges of the pad member to abut the bottom planar wall of the handle member.

3. A holding device according to claim 2 in which the peripheral edge of the pad holding plate is formed with a plurality of upwardly curved serrations.

ABE SCHIMMEL.
